UNITED STATES PATENT OFFICE.

FREDERIC J. BRYANT, OF NEW YORK, N. Y.

FIRE-ESCAPE.

No. 851,862.

Specification of Letters Patent.

Patented April 30, 1907.

Application filed December 17, 1906. Serial No. 348,263.

To all whom it may concern:

Be it known that I, FREDERIC J. BRYANT, residing at the city of New York, county and State of New York, have invented certain new and useful Improvements in Fire-Escapes, of which the following is a specification, reference being had to the accompanying drawings.

My invention relates to improvements in the construction of fire-escapes and particularly to ladders, commonly called chain ladders, used as a means of escape from a burning building.

One feature of my invention resides in the manner in which the suspensory member or chain is interlocked with the rung of the ladder; and an object of my invention is to provide a fire escape which will be simple in construction and perfectly safe in operation.

In the drawings illustrating the principle of my invention and the best mode now known to me of applying that principle, Figure 1 is a front elevation of my new fire ladder; Fig. 2 shows in end view one of the rungs; Fig. 3 is a sectional detail on line A—A, of Fig. 1; and Fig. 4 shows in sectional detail a modified form.

The rung *a* is tubular and is slotted longitudinally at each end. A link *c* of the chain *d* is slipped into the slot *e* in the end of the rung *a*, which then rests upon the enlargement or knot *f* formed in the wire. To lock the link securely in place, a common washer or annular disk *g* is slipped over the end of the rung; and the end of the rung is then upset so as to form a shoulder or flange *h*, which holds the washer securely in place.

In the form shown in Fig. 4, the end of the rung is of a smaller or reduced diameter than

is the body portion of the rung; and when 40 the end of the rung is upset, the washer *g* is locked in the groove *i*.

My new ladder is very light, easily folded into small space and very strong, all of which features are sought after in this class of apparatus.

I am aware of the patent granted to C. Mace on December 26, 1899, No. 639,902; but the permanency of the position of the rungs in the structure shown and described 50 in that patent depends upon the tightness with which the nuts are made to jam the wire cable against the walls of the aperture through which the cable passes and the permanency of the position of the nuts themselves after they have been adjusted. In my new ladder the rung *a* cannot slip along the suspensory member since it is supported by the knot *f*; and the suspensory member is not subjected to any deformation or weakening, when the washer *g* is secured in place.

I claim:

1. In a ladder, the combination of a rung formed with a slot and with an integral flange at its end; a suspensory member which passes 65 through said slot; and a washer interposed between said flange and said suspensory member.

2. In a ladder, the combination of a rung formed with a slot and with an integral flange 70 at its end; a suspensory member which passes through said slot; and a washer slidably mounted on the end of said rung between said flange and suspensory member.

FREDERIC J. BRYANT.
